TREATMENT OF HYDROCARBONS

Joseph D. Danforth, Chicago, Ill., assignor to
Universal Oil Products Company, Chicago, Ill.,
a corporation of Delaware

Application January 10, 1941, Serial No. 373,962

13 Claims. (Cl. 260—683.4)

This application is a continuation-in-part of my co-pending application Serial No. 370,323, filed December 16, 1940.

This invention relates to the continuous and successive isomerization of paraffinic hydrocarbons and alkylation of the resultant isomerized paraffins to produce higher molecular weight alkyl derivatives thereof. More specifically the process is concerned with the isomerization of normal paraffins, mildly branched chain paraffins, or mixtures thereof followed by alkylation of the resulting isomerized paraffins with olefins, these successive reactions being effected in the presence of a catalyst introduced by means of a substantially inert fluid comprising essentially one or more of the reactants charged to a reaction zone containing a packing material.

Isomerization is applicable not only to individual paraffinic hydrocarbons of straight chain structure but also to hydrocarbon mixtures containing these compounds in substantial percentages such as straight-run gasolines and their fractions which contain in addition to paraffinic hydrocarbons of highly knocking characteristics other hydrocarbons comprising some paraffinic hydrocarbons of branched chain structure and the usual run of naphthenic and aromatic hydrocarbons.

The isomerization of normal butane and of normally liquid paraffinic hydrocarbons such as normal pentane, normal hexane, etc., is frequently desirable in the manufacture of derivatives since the isomeric branched chain compounds so formed are more reactive chemically, and in the case of gasoline or gasoline fractions, the isomerization also effects a marked increase in the antiknock value of the gasolines.

Alkylation of isomerized paraffinic hydrocarbons as isoparaffins and more-highly branched chain paraffins with olefins may be effected in the presence of easily volatilizable catalysts including aluminum chloride-hydrogen chloride mixtures and boron fluoride-hydrogen fluoride mixtures which are also effective as paraffin isomerizing catalysts.

In both isomerization and alkylation reactions in the presence of a catalyst introduced as vapors it is necessary for a substantial proportion of the catalyst to be present in the reaction zone and consequently it is necessary to recycle large amounts of the catalyst particularly when the reactions are carried out in gaseous phase although they may also be carried out in liquid phase or in mixed phase as near the critical conditions where both gases and liquids may be

present in the reaction system. In order to substantially avoid the recycling of large amounts of an isomerizing and alkylating catalyst, the reaction chamber is filled with a granular packing material upon which a substantial proportion of the catalyst deposits and is retained within the reaction zone. In this way a relatively high concentration of a catalyst is kept in the reaction zone without introducing an equivalent amount of catalyst with the hydrocarbons or other fluids being charged to the process.

In one specific embodiment the present invention comprises a process for converting paraffinic hydrocarbons of essentially straight chain structures into higher boiling paraffinic hydrocarbons which comprises subjecting said paraffinic hydrocarbons of essentially straight chain structures to contact with a catalyst introduced by means of a fluid carrying medium to a reaction zone containing a granular packing material to produce a mixture containing a substantial proportion of more-highly branched chain paraffinic hydrocarbons; introducing an olefin-containing hydrocarbon fraction to said reaction zone at at least one point intermediate between the entrance and exit thereof to form a reaction product containing higher boiling paraffinic hydrocarbons; separating said reaction product into a relatively light fraction comprising essentially unconverted paraffins and isomerized paraffins, a mixture of higher boiling paraffinic hydrocarbons, and a residue; and recycling said light fraction comprising essentially unconverted paraffins and isomerized paraffins to further reaction with the added olefin-containing hydrocarbon fraction.

According to the process of the present invention normal paraffinic hydrocarbons, mildly branched chain paraffinic hydrocarbons, and mixtures thereof may be isomerized into branched and more-highly branched chain paraffinic hydrocarbons and these hydrocarbons may be reacted concurrently and continuously with olefinic hydrocarbons to produce substantial yields of higher boiling paraffinic hydrocarbons of high antiknock value. In a general way the present process is carried out by maintaining a high concentration of a volatilizable catalyst in a reaction zone without introducing an equivalent concentration of catalyst with the paraffinic hydrocarbons charged. An essential feature of the invention is the fact that the reaction zone is filled with a granular packing material, which of itself may or may not have isomerizing and alkylating activity, upon which a substantial portion of the volatilizable isomerizing and al-

ylating catalyst is deposited and retained within the reaction zone.

Suitable catalysts for both the isomerizing and alkylating reactions comprise particularly aluminum chloride but other volatilizable materials may be used satisfactorily such as aluminum bromide, mixtures of boron fluoride and hydrogen fluoride, etc. The addition of a hydrogen halide as hydrogen chloride to a hydrocarbon mixture being subjected to isomerizing and alkylating reactions may improve the operation of the process and increase the time during which the catalyst remains active. The catalyst employed may be introduced to a reaction zone containing a packing material by means of one or more of the fluids being charged thereto. The alternative catalysts which may be used, although not necessarily on an equivalent basis, may also be introduced mechanically into the reaction zone. Thus a molten salt, paste, or slurry containing aluminum chloride may be introduced to a packed reaction zone by extrusion or other suitable means of charging aluminum chloride may be employed.

When the present combination isomerization and alkylation process is catalyzed by aluminum chloride, the aluminum chloride utilized as catalyst is picked up conveniently by a carrier fluid such as hydrogen, hydrogen chloride, a paraffinic hydrocarbon, or a mixture of any two or all of these substances may be contacted with aluminum chloride in a suitable catalyst-charging vessel maintained under conditions of temperature and pressure necessary to introduce into the carrier fluid the desired proportion of aluminum chloride. Aluminum chloride so used may be present in the charging vessel as a solid, a liquid, a binary or ternary mixture with other metal halides, or as an adsorbed layer on a suitable adsorbent material. The fluid mixture containing both aluminum chloride and isomerized paraffinic hydrocarbons is then charged to a reaction zone containing a granular material which may or may not have been impregnated previously by aluminum chloride or by a mixture of one or more halides of the Friedel-Crafts type such as those of iron, zinc, aluminum, etc.

Thus aluminum chloride is charged continuously with the other reactants or intermittently so that as the isomerizing and alkylating catalyst which remains upon the packing material within the reaction zone decreases in activity during use, a further quantity of fresh aluminum chloride is introduced to the reaction zone containing the granular packing material which includes porcelain, pumice, firebrick, quartz, activated charcoal, other activated carbons, diatomaceous earth, kaolin, raw and acid-treated clays, silica gel, alumina, magnesia, zirconia, titania, composites of silica with alumina and/or zirconia, metals possessing considerable surface as spongy iron, etc. Metal halides of the Friedel-Crafts type such as the chlorides of aluminum, copper, iron, zinc, etc., may also be composited with any of the supporting materials prior to introduction into the reaction zone as packing material when such compositing is chemically or physically feasible.

The alternative reactor filling materials are not necessarily equivalent and the particular filling material employed in any specific isomerizing and alkylating reaction is dependent upon the hydrocarbons being treated, the temperature and pressure employed, the nature of the catalyst charged, and other factors.

When relatively large reactors are employed, it

may also be desirable to introduce the mixture of carrying fluid and catalyst to a reactor at various points between the inlet and outlet thereof so that the catalyst is present in exactly the optimum concentration at all points throughout the bed of granular filling material within the reactor and also so that no excess of the catalyst is present at the point of its introduction with a resulting catalyst deficiency at other points throughout the entire bed or beds of reactor filling material.

It is proposed to carry out simultaneously both isomerization and alkylation of paraffins in successive sections of a packed reaction zone in the presence of a volatile catalyst carried into said zone by one or more of the fluid reactants. When aluminum chloride is the catalyst employed, the catalyst charging zone in which aluminum chloride is picked up by one or more of the reactants is preferably maintained at a temperature between about 150° and 350° F. under a pressure of from substantially atmospheric to approximately 500 pounds per square inch. The resulting mixture of charging fluid and aluminum chloride is then introduced to a packed reaction zone maintained at a temperature between about 30° and 350° F. and preferably at a temperature generally between about 100° and 300° F. Hydrogen chloride is preferably added to the paraffinic hydrocarbon fraction charged generally to the extent of up to about 20% of its weight. It is also recommended to add hydrogen to the reaction mixture generally in a quantity of not more than about 10 mole per cent of the hydrocarbons present.

Upon entering the packed reaction zone containing aluminum chloride and preferably also hydrogen and hydrogen chloride, a substantial proportion of the paraffinic hydrocarbons undergo isomerization into branched and more-highly branched chain paraffinic hydrocarbons which are readily alkylated with olefins introduced to said packed reaction zone at one or more points intermediate between the entrance and exit thereof. Thus a portion of the packed reactor serves as a paraffin-isomerizing zone while a later section of the same reactor serves predominantly as an alkylating zone in which a small amount of isomerization may also occur. The amounts of olefinic hydrocarbons added are such that the total mixture subjected to alkylation contains between about 1 and about 20 mole per cent of olefins based upon the alkylatable hydrocarbons present.

The hydrogen and/or hydrogen chloride used to assist in the isomerizing and alkylating treatments may also be employed for carrying aluminum chloride to the packed reaction zone as it is generally desirable to carry the catalyst by means of a fluid having relatively low activity therewith. Paraffinic hydrocarbons charged or recycled in the process may also be employed for carrying the catalyst but when used for this purpose it is desirable that the catalyst-carrying fluid be substantially free from olefins which tend to polymerize in the catalyst pick-up zone and interfere with long continuous operation.

While a gas as those hereinabove indicated or an added substantially inert gas, is suitable for use as the fluid carrying the catalyst to a packed reaction zone or to a plurality of such zones, a liquid or vapors of a normally liquid material may be employed similarly. When the catalyst carrying medium is liquid, the catalyst as aluminum chloride is dissolved and/or dispersed in one or

more of the liquids charged to the process and the resulting solution and/or dispersion is thereafter charged to a reaction zone containing the packing material which will retain in said reaction zone a substantial proportion of the catalytic material charged thereto. In this way it is also possible to maintain a relatively high concentration of catalytic material in a reactor to which more catalyst is introduced continuously or intermittently with the charge to replenish the loss of catalyst which normally occurs by sublimation therefrom or by solution in the reaction mixture passing therethrough.

The alternative means which may be used for introducing an isomerizing and alkylating catalyst to a packed reaction zone by a fluid carrying medium are not necessarily equivalent and the particular means employed in any specific case depends upon the properties of the hydrocarbons undergoing treatment, the nature of the catalyst, the operating conditions employed, and other factors.

The features and advantages of the present invention will be further evident from a consideration of the following description of a characteristic operation in connection with the attached drawing which shows diagrammatically in general side elevation and without regard to exact proportioning of interconnecting units an arrangement of apparatus in which the process of the invention may be carried out. It is understood that other types of apparatus may also be employed for carrying out the process and that there are other methods of introducing a volatile catalyst to a packed reaction zone and variations in the order of mixing the reacting components which may be used in the process.

Referring to the drawing, a hydrocarbon fraction containing normal and/or mildly branched chain paraffinic hydrocarbons is admitted through line 1 and valve 2 to pump 3 which discharges through line 4 containing valve 5. All or a portion of the charged hydrocarbon fraction is directed from line 4 through line 6, valve 7, and coil 8, which receives heat from heater 9, to line 10 containing valve 11 and thence to catalyst pick-up chamber 12 maintained at such a temperature that a desired amount of the catalyst may be picked up by the fluid being passed therethrough. When aluminum chloride is used as catalyst, this material may be present in chamber 12 as a solid, a liquid, an adsorbed layer on a carrier, or as a binary or ternary mixture with other metal halides. Alternatively the catalyst may be picked up substantially by a mixture comprising essentially hydrogen, hydrogen chloride, and gases formed in the process which are introduced to line 6 from line 53 containing valve 54 as hereinafter set forth.

Although only one catalyst pick-up chamber is shown in the attached diagrammatic drawing, more than one may be employed continuously or intermittently. Thus when a fluid or when fluid reactants are being directed through chamber 12 in order to introduce catalyst to reactor 17, another chamber similar to chamber 12 may be emptied, cleaned, and refilled with a fresh charge of catalyst such as aluminum chloride so that the duplicate chamber may be used in place of chamber 12 when it becomes necessary to clean and recharge the same. From chamber 12 paraffinic hydrocarbons or a mixture containing the same and the picked-up aluminum chloride are directed through line 13 and valve 14 and com-

mingled in line 13 as hereinafter set forth with a recycled mixture containing hydrogen and hydrogen chloride, a recycled fraction containing both unconverted and isomerized paraffinic hydrocarbons and when desired, all or a portion of the paraffin-containing hydrocarbon fraction charged to the process.

Hydrogen and/or hydrogen chloride generally used in the process are introduced under suitable pressure or by a compressor, not shown, through line 15 containing valve 16 to line 13 and thence to reactor 17 containing a granular packing material. Also the mixture containing the charged paraffins, aluminum chloride, hydrogen, and hydrogen chloride being directed to reactor 17 by way of line 13 is therein commingled with a mixture of freshly charged hydrocarbons and recycled unconverted and isomerized hydrocarbons being directed through line 62 containing valve 63.

When only a portion of the freshly charged paraffin-containing fraction is directed through chamber 12 to pick up aluminum chloride catalyst, the remainder of the charged hydrocarbon fraction is passed through line 4 and valve 5 to line 58 and thence through coil 60, line 62, and valve 63 and thence through line 13 to reactor 17 containing a granular material which may consist of any one or a number of the reactor filling materials aforementioned. When desired, all of the freshly charged paraffinic hydrocarbon fraction may be directed from line 4 through line 58 to reactor 17 as described, and under these conditions gases being recycled through line 53 and valve 54 are utilized for picking up aluminum chloride in chamber 12. Freshly charged paraffinic hydrocarbons, recycled gases, or gases added by means not shown in the attached drawing, may be used singly or in any combination to carry aluminum chloride from catalyst pick-up chamber 12 through line 13 to reactor 17 containing a suitable packing material.

The alternative means for introducing aluminum chloride to a packed reaction zone by a fluid or by mechanical methods are not necessarily equivalent and the particular means chosen in any given case are dependent upon the hydrocarbons or hydrocarbon mixture being treated, the amount of catalyst employed, the conditions of operation, and other factors.

Branched chain paraffins formed by isomerization in reactor 17 are therein alkylated with olefins or with an olefin-containing hydrocarbon fraction admitted through line 18 and valve 19 to pump 20 which discharges through line 21 and valve 22 to reactor 17 at an intermediate point thereof. The olefin-containing fraction in line 21 may also be directed through branch line 23 and valve 24 to reactor 17. Although only two points of olefin addition to reactor 17 are shown in the attached drawing, the olefin may be introduced at a single point or at any number of points intermediate between the entrance and exit of reactor 17. The olefin-containing fraction in line 21 may also be commingled therein with a mixture containing paraffins and isomerized paraffins directed thereto from line 62 by way of branch line 78 containing valve 79.

The products from reactor 17 are directed through line 25, valve 26, cooler 27, line 28, and valve 29 to separator 30 in which a relatively heavy residue or sludge containing partially spent aluminum chloride is separated and withdrawn through line 31 and valve 32. Although separa-

tor 30 is shown diagrammatically as one vessel, two may be employed so as to have one in use while the other is being cleaned. When desired, said relatively heavy residue or sludge containing partially spent aluminum chloride may be recycled to further contact with the paraffins and olefins undergoing isomerizing and alkylating treatments. When desired, cooler 27 may be replaced by a suitable device for separating aluminum chloride vapors from the hydrocarbon stream. Such separation may, for example, be effected in a tower containing an adsorptive material through which the hydrocarbons pass and upon which the aluminum chloride is deposited and retained.

A mixture of products containing a substantially saturated alkylate formed from olefins and from a portion of the isoparaffin hydrocarbons present in reactor 17, the excess of unconverted and isomerized paraffins, hydrogen, and hydrogen chloride directed into separator 30 is passed therefrom through line 33 and valve 34 to fractionator 35 of conventional design in which a light fraction is substantially separated from higher boiling hydrocarbons. When it is desirable to operate fractionator 35 under a pressure above that employed in reactor 17 in order to assist in the separation of the products from the excess of the unconverted reactants and to facilitate recycling of a light fraction and of unconverted and isomerized paraffins, valve 34 is closed and the mixture of hydrocarbons, hydrogen, and hydrogen chloride is passed from line 33 through line 36 and valve 37 to pump 38 which discharges through line 39 and valve 40 to line 33 beyond valve 34 and thence to fractionator 35.

From fractionator 35 a mixture of unconverted and isomerized paraffins, hydrogen, hydrogen chloride, and relatively small amounts of normally gaseous paraffins as methane, ethane, propane, and butanes, is taken overhead through line 41, valve 42, condenser 43, run-down line 44, and valve 45 to receiver 46 equipped with conventional gas release line 47 containing valve 48 and with liquid draw-off line 49 containing valve 50. At least a portion of the normally gaseous mixture collected in receiver 46 and containing hydrogen and hydrogen chloride as well as other light gases is directed from line 47 through recycle line 51 and valve 52 to line 13, already mentioned, in which fresh hydrogen and hydrogen chloride are commingled with the other reactants as described and later conducted through line 13 to reactor 17. Although the paraffin-containing fraction introduced through line 4 is indicated in the attached diagrammatic drawing as a suitable carrying fluid for the aluminum chloride catalyst, it may also be desirable to introduce to a portion of said fraction in line 6 by way of line 53 and valve 54 a portion of the gas mixture containing hydrogen and hydrogen chloride being recycled through line 51 aforementioned.

The material present as liquid in receiver 46 is directed therefrom through line 55 and valve 56 to pump 57 which discharges through recycle line 58, valve 59, heating coil 60 which receives heat from heater 61 and then through line 62 containing valve 63 and thence through line 13 to reactor 17 aforementioned. A portion of the liquid being recycled through line 58 and comprising essentially unconverted paraffins is directed through line 64 and valve 65 to a point near the top of fractionator 35 to assist in controlling the temperatures therein.

From fractionator 35 a side cut comprising

essentially gasoline boiling range hydrocarbons is withdrawn through line 66, valve 67, condenser 68, run-down line 69, and valve 70 to receiver 71 equipped with conventional gas release line 72 containing valve 73 and with liquid draw-off line 74 containing valve 75. A substantially saturated gasoline which is the desired product of the process is withdrawn to storage through line 74 and valve 75 while a higher boiling hydrocarbon mixture is discharged from the bottom of fractionator 35 through line 76 and valve 77 to cooling and storage or to other use.

In case the aluminum chloride catalyst is picked up entirely by recycled gases, the freshly charged paraffin-containing fraction is introduced from line 4 to line 58 through which a recycle stock is being directed to heating coil 60 and thence by way of line 62, valve 63, and line 13 to further reaction in reactor 17 containing the combined isomerizing and alkylating catalyst deposited upon a granular carrier.

The following example is introduced as characteristic of the results expected from the practical operation of the process, although it is presented with no intention of thereby limiting the generally broad scope of the invention as it is possible to vary the type of reactor packing material, the amount of catalyst, the conditions of operation, etc.

Normal butane is passed through a vessel containing aluminum chloride granules maintained at 225° F. under a pressure of 200 pounds per square inch. The resulting mixture of butane and aluminum chloride carried thereby is commingled with approximately 2.5 mole per cent of hydrogen chloride and about 1 mole per cent of hydrogen and the commingled mixture is subjected to contact in a subsequent reaction zone containing crushed porcelain maintained at 220° F. After a period of operation during which aluminum chloride deposits upon the reactor packing material, and while charging normal butane at an hourly rate (measured as liquid) approximately one-fourth that of the volume of the packed reactor, approximately 25% of isobutane and 3% of pentanes are formed per pass through approximately the upper one-half of the packed reactor. A mixture of fresh and recycled butanes approximately equal in volume to that of the initially charged normal butane mixed with about 5 mole per cent of added ethylene is introduced at approximately the midpoint of the packed reactor maintained at such a temperature that after mixing with the butanes in the packed reactor the resulting reaction mixture will be at a temperature of approximately 160° F. during its passage through the remainder of the packed reactor in which isobutane reacts with ethylene to produce a higher boiling hydrocarbon fraction containing a substantial proportion of branched chain hexanes. The reaction product is discharged from the packed reactor to a separator in which a relatively small amount of aluminum chloride sludge is separated from a mixture of alkylation products and unconverted butanes. Unconverted butanes fractionated from the desired alkylation product are then recycled to further isomerization and alkylation treatment in the packed reactor as aforementioned.

The novelty and utility of the process of this invention are evident from the preceding specification and example given, although neither section is intended to unduly limit its generally

broad scope.

I claim as my invention:

1. A process for producing more valuable products from normal and mildly branched chain paraffins which comprises introducing the paraffins to the inlet end of a reaction zone containing solid packing material and passing the hydrocarbons through the packing material to the outlet end of the reaction zone, simultaneously introducing to the inlet end of the reaction zone a fluid carrying medium containing an isomerizing and alkylating catalyst, maintaining the reaction zone under conditions such as to deposit a substantial portion of the catalyst on said packing material, isomerizing at least a portion of the paraffins in the reaction zone adjacent the inlet end thereof, thereby forming isoparaffins, thereafter commingling the paraffins with olefinic hydrocarbons, the latter being introduced to the reaction zone at an intermediate point in the path of travel of the paraffins through said packing material to pass with the paraffins through the remaining portion of the reaction zone, reacting olefins with isoparaffins in said remaining portion of the reaction zone, and removing resultant reaction products from the outlet end of the reaction zone.

2. The process as defined in claim 1 further characterized in that said fluid carrying medium comprises at least a portion of said paraffins.

3. A process for producing more valuable products from normal and mildly branched chain paraffins which comprises introducing the paraffins to the inlet end of a reaction zone containing solid packing material and passing the hydrocarbons through the packing material to the outlet end of the reaction zone, simultaneously introducing to the inlet end of the reaction zone a fluid carrying medium containing aluminum chloride, maintaining the reaction zone under conditions such as to deposit at least a portion of the aluminum chloride on said packing material, isomerizing at least a portion of the paraffins in the reaction zone adjacent the inlet end thereof, thereby forming isoparaffins, thereafter commingling the paraffins with olefinic hydrocarbons, the latter being introduced to the reaction zone at an intermediate point in the path of travel of the paraffins through said packing material to pass with the paraffins through the remaining portion of the reaction zone, reacting olefins with isoparaffins in said remaining portion of the reaction zone, and removing resultant reaction products from the outlet end of the reaction zone.

4. The process as defined in claim 3 further characterized in that said fluid carrying medium comprises at least a portion of said paraffins.

5. The process as defined in claim 3 further characterized in that said fluid carrying medium comprises hydrogen chloride.

6. The process as defined in claim 3 further characterized in that said fluid carrying medium comprises hydrogen.

10 7. The process as defined in claim 1 further characterized in that said paraffins comprise normal butane.

8. The process as defined in claim 3 further characterized in that said paraffins comprise normal butane.

15 9. A hydrocarbon conversion process which comprises commingling normal paraffins with aluminum chloride and subjecting the paraffins to isomerization in the presence of the aluminum chloride, thereafter commingling olefinic hydrocarbons with the paraffin-aluminum chloride mixture and subjecting the commingled materials to alkylating conditions in a reaction zone containing solid packing material, maintaining the reaction zone under conditions such as to deposit a substantial portion of the aluminum chloride on said packing material, and removing the resultant alkylation products from the reaction zone.

20 10. The process as defined in claim 9 further characterized in that said normal paraffins comprise normal butane.

11. A hydrocarbon conversion process which comprises commingling normal paraffins with aluminum bromide and subjecting the paraffins to isomerization in the presence of the aluminum bromide, thereafter commingling olefinic hydrocarbons with the paraffin-aluminum bromide mixture and subjecting the commingled materials to alkylating conditions in a reaction zone containing solid packing material, maintaining the reaction zone under conditions such as to deposit a substantial portion of the aluminum bromide on said packing material and removing the resultant alkylation products from the reaction zone.

25 12. The process as defined in claim 1 further characterized in that said fluid carrying medium is a liquid comprising at least a portion of said paraffins.

30 13. The process as defined in claim 3 further characterized in that said fluid carrying medium is a liquid comprising at least a portion of said paraffins.

35 55 JOSEPH D. DANFORTH.
